UNITED STATES PATENT OFFICE.

FREDERICK H. JONES, OF ANDOVER, MASSACHUSETTS.

DESIGN FOR AN ELASTIC TIRE FOR VEHICLES.

43,047.

Specification for Design.

Patented Sept. 24, 1912.

Application filed May 15, 1912. Serial No. 697,558. Term of patent 14 years.

To all whom it may concern:

Be it known that I, FREDERICK H. JONES, a citizen of the United States, residing at Andover, in the county of Essex and State of Massachusetts, have invented a new, original, and ornamental Design for an Elastic Tire for Vehicles, of which the following is a specification, reference being had to the accompanying drawing, forming part thereof.

Figure 1 is a perspective view of an elas-

tic tire for vehicles, showing my new design, and Fig. 2 is a plan view of a portion of the tire.

I claim:

The ornamental design for an elastic tire for vehicles, as shown.

FREDERICK H. JONES.
